UNITED STATES PATENT OFFICE

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA

PROCESS AND APPARATUS FOR MAKING PLATE GLASS

Application filed April 7, 1928. Serial No. 268,146.

The invention relates to a process and apparatus for making plate glass, such process and apparatus being shown and described, but not claimed, in my copending application, 5 Serial Number 268,145, of even date herewith. The objects of the present invention are in the main the same as those of said copending application; namely, to provide a process and apparatus permitting the formation of glass 10 sheets whose surfaces are of such smoothness that the amount of grinding is reduced to a minimum; to provide a process and apparatus which permit the formation and handling of sheets which are much thinner than the sheets 15 heretofore made upon the regulation casting table; and to provide an apparatus which can be easily operated and is of simple construction. A further important object is to provide a process and means whereby the 20 glass is reduced to uniform thickness after it is rolled on the table. One form of apparatus for carrying out the process is shown in the accompanying drawings, wherein:

Figure 1 is a plan view. Fig. 2 is a section 25 on the line II—II of Fig. 1. And Fig. 3 is an enlarged section on the line II—II of Fig. 1 through a portion only of the apparatus.

Referring to the drawings, 1 is an inclined casting table constructed in the usual way except as to the matter of its inclination and provided with suitable cooling means including the pipes 2 by means of which water is circulated through the table. The table is supported upon suitable standards 3, 3, etc. 30 carried by a concrete foundation or one of structural steel. The table is provided along its side edges with a pair of trams 4, 4 adapted to support the roll 5 and determine the thickness of the sheet of glass which is rolled on the table. The roll 5 is hollow and suitably water cooled by means of the swivels 6, 6, to which the water pipes 7, 7 are connected. After a volume of glass is teemed behind the 35 roller, it is moved upward along the table from the full line position shown in Fig. 2 to the dotted line position A at the upper end of the table by means of the chains 8, 8 secured at their forward ends to the axle of the roll by means of suitable swivels and at their 40 other ends secured to the drums 9, 9 carried

on the shaft 10. The chains pass over a pair of sheaves 11, 11 journaled in the upper end of the standard 3 and are coiled up upon the drums when the motor 12 is operated. This motor drives the shaft 9 carrying the 55 drums through the intermediary of the gears 13.

The molten glass is brought to a position adjacent the casting table on the cars or trucks 14 from which the pots are lifted by the teeming crane 15, such crane being mounted for movement along the track 16 supported upon the columns 17. In moving from a position over the truck to pouring position over the car, the pot 18 is carried over the brush 19 (Fig. 1) for cleaning it in the usual way, after 60 which it is moved to a teeming position just to the rear of the dotted line position B of the roller 5. The glass is then teemed across the table in the usual way and the roller is moved along the table to the position A as heretofore referred to, thus rolling out the 65 sheet of glass.

After the sheet of glass has been formed upon the table, it is allowed to slide off by gravity onto the runway at the lower end of the table and into the roller leer 19 through which it is carried and annealed in the usual way. The runway is preferably constructed, 70 as indicated in Fig. 3, and consists of the water cooled platen 20 and the series of fluid cooled rollers 21. In order to prevent the end of the glass sheet from turning down into the space between the lower end of the table and the platen 20, the pipe 22 is provided having a plurality of perforations along its upper edge and a blast of air is forced through the pipe until the end of the sheet has passed onto the platen. After passing over the 75 platen, the glass sheet passes between the pair of sizing rolls 23 and 24, which serve to reduce the sheet to uniform thickness. The glass is still relatively plastic when it reaches these rolls, although provided with a skin 80 upon its upper and lower sides due to contact with the casting table and the roll 5 so that there is no difficulty in bringing it to uniform thickness. This is a desirable feature in the 85 operation as it is a difficult matter to keep the 90 surface of the casting table in a true plane 95 100

so that, unless it is subsequently sized, the sheet produced may vary considerably at different points in its length. This difficulty as to securing uniform thickness is also increased by distortion of the roll 5 due to the fact that it becomes highly heated on one side when the mass of molten glass is first teemed behind it which tends to make it bulge on the side in contact with the glass. The rolls 23 and 24 are provided with swivels 26, 26 at their ends, to which the water pipes 27, 27 are connected for circulating a cooling fluid through the rolls. The runway comprising the platen 20 and the rolls 21 and also the sizing rolls 23 and 24 are carried upon a framework 28 upon the truck 29 to permit this apparatus to be moved from between the casting table and the leer, this being a matter of convenience in case replacements or repairs are necessary. The truck is mounted upon the tracks 30 and power means are provided for moving the truck in the form of a screw 31 driven by the motor 32 and passing through a nut carried by the frame 28. The leer rolls 33 are provided at their ends with sprocket wheels and these are driven from the chains 35, 36, etc. These chains are in turn driven from the countershaft 37 (Fig. 1) through the intermediary of reduction gearing in the casings 38 and 39 and the countershafts 40 and 41, such countershafts being provided with sprocket wheels around which the chains 35, 36 pass. The apron rolls 21 and the sizing rolls 23 and 24 are also driven from the shaft 31 through the intermediary of the tumbler shafts 42 and 43 (Fig. 1), together with suitable reduction gearing in the casing 44, and chain and sprocket drives similar to those described in connection with the leer rolls.

The frame 28 which carries the platen 20 and rolls 21 also carries two pairs of rolls 45 (Fig. 3) for supporting the roll 5 when such roll is not in service, the position of the roll at such time being indicated in Fig. 3 by the dotted circle marked C. The rolls 45 may be suitably driven by any means, such as those described in my copending application so that the roll 5 is kept rotating between operations. This is desirable as the rolls should be kept heated by means of a gas burner playing upon one side and the constant rotation prevents the roll from becoming overheated on one side. After a sheet of glass has been rolled onto the table 1 and allowed to slide off by gravity, the roll 5 is moved back from the position A (Fig. 2) to position C so that the apparatus is ready for another casting operation. The angle of the table 1 is preferably such that the sheet will move off of the table by gravity after the roll 5 has passed off of the table and assumed the position A of Fig. 2, but the invention is not limited to making the table at an angle as steep as this, in which case some assistance may be

given to the sheet in order to start it on its downward movement and keep it going if necessary. It is preferable, however, to avoid the application of any pressure tending to deform the sheet either by stretching or compressing it. The use of the sizing rolls 23 and 24 is not limited to a construction in which the table 1 is permanently tilted as this feature of the invention is just as applicable in a construction such as that of my copending application, wherein the table is normally in a horizontal position and is tilted to stow the sheet by gravity. 70 75

What I claim is:

1. A process of making a glass sheet which consists in teeming a body of glass across the lower end of a casting table which is inclined upwardly from said lower end, rolling such glass upwardly along the table to form a sheet thereon, permitting the sheet as thus formed and while still plastic to slide from the table, supporting the sheet as it leaves the table and carrying it forwardly through an annealing leer. 80 85

2. A process of making a glass sheet, which consists in teeming a body of molten glass across a flat supporting surface, rolling the glass into a sheet on said surface, causing the sheet to slide in part at least by the influence of gravity from the table and over a runway while it is still relatively plastic, and rolling the sheet to substantially uniform thickness during its movement off of the table and over the runway and while it has sufficient residual heat and plasticity to permit such sizing operation. 90 95 100

3. Apparatus for making a glass sheet comprising a casting table fixed in inclined position and having a flat, plain surface for receiving the glass, a roll mounted for movement along the table from its lower to its upper end and adapted to roll out into a sheet a body of molten glass teemed across the lower end of the table, a roller leer in alignment with the table, and a runway leading from the lower end of the table into the leer. 105 110

4. Apparatus for making a glass sheet comprising a casting table fixed in inclined position and having a flat, plain surface for receiving the glass, a roll mounted for movement along the table from its lower to its upper end and adapted to roll out into a sheet a body of molten glass teemed across the lower end of the table, and a laterally extending roller runway and leer leading from the lower end of the table. 115 120

5. Apparatus for making a glass sheet comprising a casting table fixed in inclined position and having a flat, plain surface for receiving the glass, a roll mounted for movement along the table from its lower to its upper end and adapted to roll out into a sheet a body of molten glass teemed across the lower end of the table, and a laterally extending roller runway and leer leading from the lower 125 130

end of the table, a part at least of the rollers being driven by one way clutch means which permit the sheet as it moves over such rollers to move them forwardly at a higher rate of speed than that at which they are driven.

6. Apparatus for making a glass sheet comprising a casting table fixed in inclined position and having a flat, plain surface for receiving the glass, a roll mounted for movement along the table from its lower to its upper end and adapted to roll out into a sheet a body of molten glass teemed across the lower end of the table, and a runway extending laterally from the lower end of the table and adapted to receive and carry away the glass sheet as it slides off of the table, the table being inclined at an angle such that the glass sheet will slide down it due to the action of gravity.
- 10 7. Apparatus for making a glass sheet comprising a casting table fixed in inclined position and having a flat, plain surface for receiving the glass, a roll mounted for movement along the table from its lower to its upper end and adapted to roll out into a sheet a body of molten glass teemed across the lower end of the table, a runway extending laterally from the lower end of the table and adapted to receive the sheet as it slides off of the table, and means for rolling the sheet to substantially uniform thickness as it passes over the runway.
